STOP OPERATING MECHANISM

James F. Koca, Woodstock, Ill., assignor to
Woodstock Typewriter Company, Woodstock,
Ill., a corporation of Illinois

Application May 20, 1935, Serial No. 22,301

5 Claims. (Cl. 197—179)

This invention relates to typewriters and particularly to an attachment therefor. More specifically, the invention relates to stops carried by the carriage and adapted to co-operate with a stop member operated by the depression of a key to engage the carriage stops, to stop the carriage at predetermined positions.

An important object of the invention is the provision of a stop adapted to be adjusted in upper, non-engaged position or lower, operative, engaged position, said stop being positioned by the depression or operation of a co-operating depressing member.

Another object of the invention is the provision of a stop setting element for setting any one of a plurality of stops in a predetermined position.

A further object of the invention is the provision of a plurality of slidably mounted elements for selectively depressing stops into position to be engaged by a stop member.

Numerous other objects and advantages will be apparent throughout the progress of the following specification.

The accompanying drawings illustrate a selected embodiment of the invention, and the views therein are as follows:

Fig. 1 is a detail side elevation of a typewriter embodying the invention.

Fig. 2 is a detail top plan view.

Fig. 3 is a detail sectional view on the line 3—3 of Fig. 2.

Fig. 4 is a detail sectional view on the line 4—4 of Fig. 3.

Fig. 5 is a detail sectional view showing the depressing member in depressed position and moving a carriage stop to operative position.

Fig. 6 is a detail sectional view on the line 6—6 of Fig. 5.

The particular typewriter herein shown for the purpose of illustration is that of the popular, well known "Woodstock" typewriter, but it is to be understood that the invention is applicable to typewriters of other make. The typewriter or typewriting machine herein illustrated has a frame 11 upon which a carriage 12 is mounted for transverse movement on ways 13. A circular bar or rod 14 extends between the end plates 15 of the platen carriage, and this bar is rigidly attached to the end plates 15, being held from rotation. A plurality of column stops 16 are journaled on the bar 14 and normally project upwardly therefrom in normal inoperative position, as shown in Fig. 3. The stops 16 are arranged substantially throughout the entire length of the

bar 14 and are spaced one from another by letter space distances.

Each stop 16 comprises a metal body 17 having a circular receiving opening or hole 18 through which the bar 14 extends. The end 19 of the body 17 is cut out, as indicated at 20, and extends into the opening 18. The body 17 of the stop 16 is split or cut, as indicated at 21, Figs. 3 and 5, to form an extending arm or end 22. The stop is preferably cut or stamped from metal and is hardened sufficiently so that the extension or leg 22 will be relatively springy and capable of spreading a predetermined distance so that it may be easily and readily slipped over the rod 14.

The stops 16 are movable in an upward inoperative position, as shown in Fig. 3, or into a downward operative position, as shown in Fig. 5. Upper and lower bars 23 and 24 prevent lateral movement of the stops as well as limiting the upward and downward movement thereof. The stops 16 are arranged in cut-out notches or spaces 25 and 26 in the bars 23 and 24, the slots 25 and 26 being in alignment with each other. The stops 16 are held in either of their adjusted positions by means of teeth 27 formed on the extension or leg 22 of each stop. These teeth co-operate with and are adapted to engage the opposite sides of a rib 28 formed on the circular bar 14. Due to the pivoted and yielding connection of each stop 16 with the bar 14, the stops 16 may be readily and quickly removed and applied to the bar 14. The stops 16 may be moved from inoperative raised position, as shown in Fig. 3, to operative position, as shown in Fig. 5, by a finger 29, Fig. 3, connected to a bar 30, which moves vertically in a housing 31. The finger 29 is depressed by the operation of a key 32, Fig. 1. When the stop is in down position it is adapted to engage a stop member 33 which is also slidably mounted in the casing 31 and is raised upwardly by the depression of a key 34.

The particular construction of the stop 16, the method of depressing the same by the finger 29, and the means for operating the stop member 33, are disclosed and claimed in applicant's co-pending application, Serial No. 22,300, filed concurrently herewith. A different type of a stop and means for depressing the stop are also disclosed and claimed in another of applicant's co-pending applications, Serial No. 22,299, filed concurrently herewith, both of the aforesaid co-pending applications being assigned to the present assignee.

Very often the operator or typist, particularly when writing various forms of letters, finds it

- desirable to have certain stops set to conform with these regular forms or routine and, therefore, it is more convenient to throw the stops by hand. In the aforesaid co-pending application, Serial No. 22,300, some of the stops are provided with an extension or handle having a colored knob. However, it is even still more convenient to have slidable means co-operating with the stop whereby any stop may be depressed as desired, without resorting to the operation of the key lever. This latter construction forms the basis of the present application, and comprises manually depressible members 35, each of which has a finger piece or key 36 and an elongated vertically extending plunger bar or rod 37. Each member 35 is mounted in a metal clip 38, Fig. 4, which is preferably stamped and formed from a single piece of metal and comprises a base portion 39, which is adapted to abut the upper surface 40 of the top bar 23. Integral portions 41 extend downwardly at the front and back of the bar 23 and are provided with in-turned edges 42 which extend into longitudinal grooves or slots 43 formed in the front and back of the bar 23, Fig. 5.
37. An upstanding body portion 44, forming part of the member 38, is provided with alined openings through which the body or plunger portion 37 extends. A pin 45, Fig. 3, limits the upward movement of each member 35, and a spring 46 arranged between the bent ears 47 and 48 urges the member 35 upwardly, the spring 46 engaging a washer 49 which engages the pin 45, Fig. 5.
- Ears or arms 50 are bent up from the plane of the member 39 and provide means for shifting each of the elements along the bar 23. A spring clip 51 is fixed to the back of the body portion 44 in any convenient manner, such as by screws 52, for holding each of the members 35 in adjusted or shifted position and preventing unauthorized side movement. A detent 53 is formed in the spring metal member 51, Fig. 6, and is adapted to engage the spaces 25 in the bar 23 to hold each of the elements 35 in its shifted position. The member 51 being made of spring metal, will give sufficiently to permit the members 35 to be easily slid along the bar 23, but at the same time prevents the members 35 from moving due to jar or vibration in operation.
- The invention provides manually operated members slidably mounted along the upper bar whereby the operator is free to depress any of the stops 16 as desired. To assist the operator the knobs or keys 36 may be colored differently to conform with the routine or form which the operator or typist desires. Thus, when the operator writes one form of letter, it is desired to have certain stops set in predetermined positions and these may be set in such positions by operating a member 35 which has a red knob 36.
- In still another instance, the operator may change to a form of letter writing requiring blue knobs to be shifted. The knobs may be made any color, such as red, blue, yellow, etc., so that the operator at a glance can set a stop conforming to the type of work being done. In addition, the operator is free to set any other such stops as are desired by the operation of the key lever 32. The invention, therefore, provides selective means of broad adaptation for conveniently setting the stop position of the carriage to conform with the various classes or forms of material the operator is writing. Also, the operator is free

to shift stops manually as desired or required, and the various coloring of the knobs indicates quickly the stops which are to be depressed for the certain form or routine. Changes in the routine or form, of course, can be changed at will because the members 35 are slidable. The elements 35 can be very economically manufactured, are efficient in operation and can be easily operated or manipulated.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A typewriter comprising a frame, a carriage slidable on the frame, a bar carried by the carriage, spaced slotted rods juxtaposed with respect to the bar, the slots in said rods being in alinement, stops on said bar and movable in alined slots in the rods, and a stop plunger slidable on one of said rods for selectively depressing said stops.

2. A typewriter stop depressor comprising a rod having grooves therein, a member slidable on the rod and having a body, portions of said body extending into the grooves, side arms turned up from the body and forming means for manually sliding the member on the rod, a back member on the body, spaced ears extending from the back member, and a plunger operable in the spaced ears.

3. A typewriter stop depressor comprising a rod having grooves therein, a member slidable on the rod and having a body, portions of said body extending into the grooves, side arms turned up from the body and forming means for manually sliding the member on the rod, a back member on the body, spaced ears extending from the back member, a plunger operable in the spaced ears, a spring encircling the plunger and arranged between the ears, said spring having operable engagement with the plunger to urge the plunger into a predetermined position.

4. A tabulator mechanism for a typewriter comprising a rod rigidly mounted to the carriage, a slotted bar movably mounted on the carriage, said bar being juxtaposed with respect to the rod so as to be parallel thereto and to rotate about said rod, manually operated means associated with said bar whereby said bar may be rotated at will, a plurality of stop members rotatably mounted on said rod and adapted to operate in predetermined slots on the bar, and plunger means slidably mounted on the carriage adapted to selectively engage any desired stop member and move it into operative position.

5. A tabulator mechanism for a typewriter comprising a carriage, a rod rigidly mounted to the carriage, a plurality of stop members rotatably mounted on said rod and adapted to be resiliently retained in either of two rotational positions, said stop members in one of said positions being operative to stop the carriage, said stop members being spaced in accordance with letter-space distances and being mounted at points corresponding to each point of columnar tabulation, and plunger means slidably mounted on the carriage adapted to selectively engage a desired stop member and move it to operative position.

JAMES F. KOCA.
